UNITED STATES PATENT OFFICE.

FRANK E. SAGENDORPH, OF CINCINNATI, OHIO.

METALLIC JOINT FOR FLEXIBLE ROOFING.

SPECIFICATION forming part of Letters Patent No. 257,616, dated May 9, 1882.

Application filed January 25, 1882. (No model.)

To all whom it may concern:

Be it known that I, FRANK E. SAGENDORPH, of Cincinnati, in the county of Hamilton and State of Ohio, have invented certain new and useful Improvements in Metallic Joints for Flexible Roofing; and I do hereby declare that the following is a full, clear, and exact description of the invention, which will enable others skilled in the art to which it appertains to make and use the same, reference being had to the accompanying drawings, which form a part of this specification.

Figure 1 is a plan view, a portion of one of the roofing-strips having been partially unfolded for the purpose of more fully illustrating the invention; and Fig. 2 is a sectional view on the line $x-x$, Fig. 1.

Similar letters of reference indicate corresponding parts in both figures.

This invention relates to a metal joint for roofing, constructed of flexible material, such as canvas, felt, paper, cloth, asbestos, and the like; and it consists in the improved construction of said joint, which will be hereinafter fully described, and particularly pointed out in the claim.

In the drawings hereto annexed, A represents a strip of sheet metal, the lower edge of which is bent or doubled, as shown at B, so as 30 to form a smooth or rounded edge, C.

D D' are the strips of roofing material, which, as stated, may be of paper, felt, cloth, or any other suitable flexible material. The lower-most strip, D, having been put in place upon the roof, as shown, and having its sides and lower edge secured by nails or tacks, I place upon the upper edge of said strip D the lower edge of the next strip, D', which said strip D' is reversed, or placed with its under side uppermost, this, however, being of course only necessary when the roofing material has a right and wrong side, which is not always the case.

Upon the contiguous edges of the strips D D',

I place the strip A, with its smooth or rounded edge C downward, and secure said strip by-nails driven through it and through the contiguous edges of the strips D D', which are thus secured in place. The strip D' is now folded up over the strip A, covering said strip and the nails or fastenings out of sight and protecting them from the damaging influences of the weather. Upon the upper edge of strip D', I now place the lower edge of another roofing-strip, on top of this another strip, A, and proceed as before until the entire roof is covered.

In this manner a neat, durable, and water-proof joint is formed rapidly and in an inexpensive manner. The rounded edge C of the metallic joint-strip A protects the roofing material from being cut or injured, and the roofing material is in this manner fastened more securely than by other methods with which I am acquainted.

Having thus described my invention, I claim and desire to secure by Letters Patent of the United States—

The herein-described joint for flexible roofing, consisting of the combination of a lower sheet, an uppersheet whose undeturned lower edge is applied to register with the upper edge of the lower sheet, a strip of sheet metal having its lower edge bent or doubled under so as to form a smooth rounded lower edge, and interposed within the fold of the upper sheet, and suitable fastenings passing through the said sheets, underneath, and covered by the outer fold of the upper sheet, as set forth.

In testimony that I claim the foregoing as my own I have hereto affixed my signature in presence of two witnesses.

FRANK E. SAGENDORPH.
